LIFTING APPARATUS FOR CONSTRUCTION MATERIALS

William P. Neil, Pasadena, Calif.

Application August 27, 1952, Serial No. 306,622

8 Claims. (Cl. 294—67)

This invention relates generally to the building construction art and more particularly to an apparatus employed in connection with the erection of buildings. Specifically, the invention is concerned with a lifting apparatus for facilitating the lifting and placing of roof joists between the spaced, parallel roof trusses of large building structures.

In the erection of large industrial buildings, it is common practice to provide a plurality of columns arranged in rows, such columns serving as supports for the ends of roof trusses. Roof joists are then positioned transversely of the planes of adjacent lines of the roof trusses, the ends of each joist being suitably secured to opposite, parallel trusses to extend therebetween, or to trusses and a parallel wall. In order to place a heavy joist in position, it is common practice to employ a boom-type crane, the lifting cable of which is suitably connected, as by the use of a sling, to the joist, the boom then being operated to lift the joist to the level at which the joist is to be placed between the trusses or rafters. Workmen positioned on the trusses or rafters guide the ends of each joist into U-shaped straps or stirrups provided at the facing sides of the rafters or the upper members of the roof trusses, said ends then being secured to the trusses in the usual manner. Thus, the heavy joists are lifted singly from the floor of the building and installed individually between the roof trusses.

Such a procedure is obviously time-consuming and results not only in delaying completion of the building but also in increased construction costs. Moreover, since the joists being set in position may be large and heavy, for example a 4 x 12 having a length approximately twenty to thirty feet, and is freely swingable at the end of the boom cable, it is apparent that this manner of handling the joists presents a very serious safety hazard, particularly to the workmen stationed atop the trusses, it being a common occurrence for a workman to lose his balance or footing and fall when attempting to guide such a long, heavy beam into place. Such loss of balance may also occur when a workman walks out along the placed roof joists to disconnect the hoisting cable therefrom. While the several disadvantages of handling and placing the roof joists by the conventional method discussed above have long been recognized, no satisfactory solution to the problem has been proposed, to my knowledge.

It is therefore an object of this invention to obviate the inefficiencies and hazardous conditions encountered in conventional methods of erecting roofs of large buildings by providing an apparatus capable of handling simultaneously a plurality of roof joists and operative to position the joists singly in position between the roof trusses, by a systematic and orderly procedure.

Another object of the invention is to provide a lifting and positioning apparatus which includes a liftable rack-like holder or carrier which is adapted to support a plurality of the roof joists in horizontal position, the carrier

being loaded with the joists when positioned on the floor beneath the roof trusses.

Another object is to provide an apparatus of the character referred to in which the carrier is provided with wheels or casters by which it may be conveniently moved along a floor to a loading point to receive the roof joists and then rolled to a location beneath the trusses between which the joists are to be mounted or installed.

Another object is to provide an apparatus of the class indicated in which the carrier frame is provided with a plurality of transversely extending platforms or shelves arranged in stepped relation, each shelf being adapted to support one of the roof joists. A related object is to provide on the riser of each step-like shelf retainer fingers or bars which overlie the inner tread portion of the next lower shelf and define, with said tread and the intermediate riser portion, a horizontal slot for receiving the longitudinal edge of one of the joists.

Another object is to provide a carrier for the roof joists which is formed at one end with an extension or arm adapted to be engaged by the lifting hook at the end of the cable of a mobile boom-type crane. By this means, the carrier, together with the several roof joists mounted thereon, may be lifted bodily to the approximate level of the trusses or rafters between which the joists are to be placed. Since the extension is disposed at the end of the carrier most remote from the horizontal joist-receiving slots, when the carrier is tilted upwardly through ninety degrees from its normal horizontal position on the floor, the joists are likewise turned to a position where their flat sides are substantially vertical, the lower longitudinal edge portions of the joists being retained within the slots to rest upon the now horizontal riser portions. Thus, the joists are individually supported in stepped relation and may be successively positioned between the longitudinal upper members of the parallel trusses of the roof structure.

The procedure followed in so positioning the joists involves first lifting the carrier above the level of the rafters and positioning the carrier so that the lowermost joist thereon extends at right-angles to the parallel trusses, lowering the carrier and simultaneously guiding the ends of the lowermost joist into position between the trusses and preferably into U-shaped straps or stirrups on the trusses, lowering the carrier slightly to disconnect it from said placed joist, moving the carrier laterally to a position where the next upper joist is to be located between the trusses, lowering the carrier to dispose this second joist between the trusses, and continuing this procedure until the several joists have been installed in place between the trusses, the empty carrier then being lowered onto the floor in readiness to receive another supply of the roof joists, this systematic procedure continuing until all the joists have been erected.

In accordance with the preferred method, at least two of the carriers are employed, one carrier being loaded while the other carrier is operating to install previously loaded series of the joists between the trusses. Thus, by this systematic procedure of installing the roof joists, the time involved in constructing the building roof is minimized and this results in a greatly decreased over-all building cost. Since the loaded carrier is quite stable and may be easily and safely maneuvered by the workmen positioned on the trusses when guiding the ends of the joists into place, the danger of the workmen losing their balance is also minimized. In addition, since the lifting cable is connected to the carrier, instead of to the individual roof joists, and is detached from the carrier only after the latter has been returned to its re-loading position upon the floor, the necessity for walking out on a positioned joist to disconnect the cable therefrom is wholly avoided and this also makes for greater safety.

A further object of the invention is to provide a carrier of the type specified which embodies a framework constructed entirely from structural shapes welded together, the carrier also having brake-like feet at one end which provide fulcrums about which the carrier may be tilted upwardly or pivoted downwardly to avoid rolling of the carrier during such movement.

A still further object of the invention is to provide a lifting apparatus, of the character referred to, which is extremely simple in construction and economical to manufacture, one which is comparatively light in weight and easily maneuvered, and one which is highly practical and efficient in performing its intended function.

Further objects will become apparent from the following description and from the drawings, which are intended for the purpose of illustration only, and in which:

Fig. 1 is a perspective view of a portion of a roof structure, showing the present lifting apparatus applied to use in setting a plurality of roof joists in position between parallel roof trusses;

Fig. 2 is a perspective view of the mobile and liftable carrier for supporting the plurality of roof joists;

Fig. 3 is a plan view of the carrier; and

Fig. 4 is a side elevational view of the carrier which is shown in an inclined position assumed when it is being lifted from the floor or lowered onto the same; and

Fig. 5 is a small scale sectional view, taken on line 5—5 of Fig. 1.

Referring first to Fig. 1 of the drawings, the present lifting apparatus 5 is designed particularly for use in lifting roof joists 6 into position where they may be mounted between the upper members 7 of Fink-type roof trusses 8 or to horizontal roof members 9 connecting the adjacent ends of said members of the aligned trusses. It is to be understood that the lifting and positioning apparatus of the instant invention is not limited to use in connection with a roof structure of the specific type shown but rather is adaptable for use in lifting and positioning roof joists between other forms of roof trusses and rafters. The roof structure shown, by way of example, has been successfully employed in connection with large industrial buildings of the so-called "precast, tilt-up panel" types, such a structure being disclosed in my pending application, Serial No. 286,791, filed May 8, 1952, and titled Concrete Buildings and Method of Producing Same, to which reference is made for a more detailed description of such a building. In general, a building of this type consists of a concrete floor, concrete footings bordering the floor and a series of concrete wall columns and panels precast upon the floor and tilted up into position upon the footings to form the walls of the building, the wall columns being formed either integrally with the panels or cast as separate elements to which the panels are suitably joined to provide the wall. In addition to the wall columns, other interior columns, such as those shown at 11, are set up upon footings and arranged in alignment across the building. The roof trusses 8 are set up in parallel rows with their ends resting upon bearing portions 12 of the inner columns 11 and upon bearing portions of 13 of the outer wall columns, shown in the pending application referred to above. In mounting the roof joists 6 between the trusses 8, the latter are provided with double U-shaped straps or stirrups 15 for receiving the ends of the joists, said ends being lowered into the stirrups and thereafter secured to the members 7 and 9 by the usual toe nails.

The roof joists are, according to the conventional procedure, lifted individually from the floor upon which they are stacked, by means of a mobile crane unit having a movable boom and a lifting cable detachably connectible to each joist by means of a sling. Each roof joist is lifted to a position above the parallel trusses, turned to extend normal to the trusses and then lowered into position between the trusses, workmen stationed on the trusses guiding the ends of the joist into the U-shaped stirrups. A

workman then disconnects the sling from the joist, after which the lifting cable is lowered to receive another joist. As previously pointed out, such a conventional procedure is a slow, laborious and expensive one and the over-all cost of erecting the building, based on the man-hours involved, thus is materially increased. This is an extremely important consideration where the otherwise inexpensive, precast, tilt-up method of construction is involved. The instant invention is concerned with an apparatus designed particularly for expediting the erection of such roof structures by permitting the simultaneous lifting of a plurality of the roof joists to be installed between the trusses by simply lowering the joists individually and successively into position for attachment to the trusses. In accordance with my invention, this concept involves the use of a frame-like holder or carrier 20, to be next described.

Referring particularly to Fig. 2 of the drawings, the carrier 20 is in the form of a rectangular frame or chassis having end members 21 and 22 and side members 23 and 24, all of which are preferably made from structural sections, such as strips of angle-irons. Attached to the underside of the frame, at the corners thereof, are caster units 25 having swivel caster wheels 26. The carrier frame also has upright corner posts 28 and 29, and a lateral extension or arm 30 at its forward end consisting of a pair of convergent bars 31. The outer end of the extension 30 carries a plate 32 provided with a relatively large hole or eye 33 through which the hook of a lifting cable may engage.

The sides of the mobile carrier 20 are composed of upright angle-iron bars 36, 37 and 38, and longitudinally extending angle-iron bars 39, 40, 41 and 42 extending between the uprights and the corner posts 28, 29, these several components preferably being welded together, and to the frame 21—24, to provide a strong, rigid unitary structure. Cross-struts or ties 43 and 44, extending transversely between the sides of the carrier further strengthen the structure.

It is to be noted that the longitudinal side bars 39 to 42 at each side of the carrier 20 are arranged at progressively higher levels, in other words in upwardly stepped relation from the end of the carrier at which the lifting arm 30 is located, these horizontal bars being, in effect, the treads of the steps while the uprights 36, 37 and 38 and corner posts 28, 29 constitute the risers. As will presently appear, the horizontal treads 39 to 42 provide supports for the roof joists 6 when the carrier is at rest upon the floor while the risers 36 to 38 and the rear corner posts 29 form such supports when the carrier is lifted with its forward end 30 uppermost. In order to retain the roof joists 6 on the carrier 20, each riser is provided with a lateral finger or retainer bar 48, said bars overlying the rearward portions of the horizontal treads and defining therewith slots 49 in which the longitudinal edges of the joists 6 are disposed when mounted on the carrier.

The carrier 20 is further provided with blocks 50 at its rearward end for the purpose to be later explained. The rearward corner posts 29 are provided with holes through which guiding ropes 52 may be detachably looped.

Assuming that the building construction has progressed to the stage where the roof trusses 8 have been erected to extend between the columns 11 and it is now necessary to mount the joists 6 between the trusses, such placing of the joists is carried out in the manner to be next explained. With the carrier 20 at rest upon the floor 60 of the building, roof joists 6 are placed on the carrier as indicated by the broken lines in Fig. 2. To so load the carrier 20, a joist 6a is taken from a stack of the joists and placed upon the uppermost supports 42 and slid rearwardly to cause its longitudinal edge to be located in the slot 49. Other joists 6b, 6c, and 6d are similarly and successively placed on the supports 41, 40, and 39 with their longitudinal edges disposed beneath the retainer bars 48. When so mounted on the carrier 20, the several joists 6a to 6d are arranged

in stepped relation, both horizontally and vertically, as shown. The loaded carrier 20 is then wheeled along the floor to assume a position beneath and between two rows of trusses 8.

A mobile crane is so stationed as to locate its boom between the parallel trusses 8, said crane boom having a lifting cable 55 provided with a hook 56 at its end. The hook is passed through the eye 33 of the carrier and the cable is wound onto the usual drum to raise the hook. Thus, the forward end of the carrier 20 is elevated, causing the carrier to tilt upwardly from a position on the floor where its supports 39 to 42 and the joists thereon are arranged horizontally, to an upright position where the supports 39 to 42 are disposed vertically and the bars 36 to 38 and corner posts 29 are positioned horizontally, so as to cause the joists to be arranged with their flat sides vertical. When the carrier 20 is tilted to the latter position, the joists 6a to 6d assume a stepped relation with the formerly rearmost joist 6a disposed lowermost and spaced furthermost laterally from the frame or chassis 21, 24. Thus, the several joists 6a to 6d are supported by the bars 36 to 38 and corner posts 29, and are retained on the carrier by reason of their being held in the slots 49. During the upward tilting movement of the carrier 20, the latter pivots on the blocks 50 to prevent rolling movement of the carrier on its rearward wheels which might cause injury to the workmen and upsetting of the carrier and displacement of the joists.

The carrier 20, together with the joists mounted thereon, is next lifted by the crane to a position between the parallel trusses 8 and during this upward movement the carrier is rotated laterally by means of the ropes 52, to allow the ends of the joists 9 to clear the trusses. After the carrier 20 has been raised to a position above the trusses, it is turned to a position wherein the joists extend normal to the planes of the trusses, after which the carrier is lowered gradually. During this lowering movement, workmen stationed atop the trusses grasp the ends of the lowermost joist 6a and guide it into the opposite stirrups 15. In this manner the lowermost joist 6a is quickly positioned to form part of the roof structure.

The second roof joist 6b is next positioned by first lowering the carrier 20 to adapt the lower retainer finger 48 to clear the lower edge of the placed joist 6a, after which the carrier is moved laterally toward the next pair of stirrups 15. When the joist 6b is disposed above these stirrups, the carrier is again lowered gradually and the workmen guide the ends of the joist 6b into place.

The above operation is repeated until the remaining joists 6c and 6d have been set successively in position between the trusses. The empty carrier 20 then is lowered by the crane and as its lower end approaches the floor 60, the blocks 50 engage the floor and serve as brakes to prevent undue rolling of the carrier as the latter is allowed to pivot downwardly to its horizontal loading position. The cable 55 is finally disconnected from the carrier so that the latter may be wheeled to a location to receive another set of the joists. It is to be noted at this point that the placing of the joists in the roof structure is further expedited when two or more of the carriers 20 are employed, in which case one carrier is loaded with joists while another is being operated to place its previously loaded joists between the trusses.

It will be observed from the foregoing that the present invention provides a simple, yet highly practical and efficient means for facilitating the placing of roof joists in position between the roof trusses of a building. By my lifting apparatus, the joists are quickly and systematically placed between the trusses so that the time involved in building the roof structure is greatly minimized. To be more specific, by the use of the instant carrier, several joists are lifted simultaneously into position so that the time usually involved in placing a plu-

rality of the joists in position is reduced to a minimum. For example, by simultaneously lifting four of the joists by means of the present carrier, the time involved in placing all of the joists of the roof structure is reduced to approximately one-fourth of that usually required when the conventional method of individually lifting and placing the joists is practiced. Consequently, the use of my carrier results in a very substantial reduction in man-hours of work and this is reflected in a much lower over-all cost of the building structure.

In accordance with the provisions of the patent statutes, I have described the principle of my invention, together with the apparatus which I now consider to represent the best embodiment thereof, but I desire to have it understood that the invention may be carried out by further modified means.

I claim as my invention:

1. A liftable carrier for use in placing joists to extend between parallel roof elements, comprising: a frame 20 tiltable on one end from a horizontal loading position to a vertical lifting position; wheel means on said frame by which the carrier may be moved along a floor; a plurality of support means on said frame, each adapted to support a joist placed thereon; retainer means integral with said support means and defining therewith transversely-spaced slots for laterally receiving longitudinal edges of the joists when the frame is in its horizontal loading position and operative to prevent lateral displacement of the joists when the frame is in its vertical lifting position; and a rigid lifting means at the opposite end of the frame by which the carrier can be tilted upwardly and lifted bodily by a crane to a position between said parallel roof elements, said carrier being movable successively downwardly and laterally by the crane so as to deposit the joists carried thereby singly and successively along and between the roof elements, said downward movement of the carrier releasing the joists from said slots.

2. A liftable carrier for use in placing joists to extend between parallel roof elements, comprising: a frame 40 tiltable on one end from a horizontal loading position to a vertical lifting position; caster wheel on said frame by which the carrier may be moved along a floor; a plurality of support means at the sides of said frame, each adapted to support a joist placed thereon; retainer means at the sides of the frame integral with each of said support means and defining, with another of said support means, transversely-spaced, horizontally extending slots for laterally receiving longitudinal edges of the joists when the frame is in its horizontal loading position and operative to prevent lateral displacement of the joists when the frame is in its vertical lifting position; and an extension integral with the frame and providing a lifting means at the opposite end of the frame by which the carrier can be tilted upwardly and lifted bodily by a crane to a position between said parallel roof elements, said carrier being movable successively downwardly and laterally by the crane so as to deposit the joists carried thereby singly and successively along and between the roof elements, said downward movement of the carrier releasing the joists from said slots.

3. A liftable carrier for use in placing joists to extend between parallel roof elements, comprising: a rectangular frame 65 tiltable on one end from a horizontal loading position to a vertical lifting position; caster wheels on said frame by which the carrier may be moved along a floor; a plurality of support means at the sides of said frame, each pair of support means being adapted to support a joist placed thereon, said support means being arranged in stepped relation; retainer means integral with each supporting means, each retainer means overlying the next lower support means and defining therewith horizontally extending slots for laterally receiving longitudinal edges of the joists when the frame is in its horizontal loading position and operative to prevent lateral displacement of the joists when the frame is in its vertical lifting position;

and an extension integral with the frame and providing a lifting means at the opposite end of the frame by which the carrier can be tilted upwardly and lifted bodily by a crane to a position between said parallel roof elements, said carrier being movable successively downwardly and laterally by the crane so as to deposit the joists carried thereby singly and successively along and between the roof elements, said downward movement of the carrier releasing the joists from said slots.

4. A liftable carrier for use in placing joists to extend between parallel roof elements, comprising: a rectangular frame tiltable on one end from a horizontal loading position to a vertical lifting position; caster wheels on said frame by which the carrier may be moved along a floor; a plurality of support means at the sides of said frame, each adapted to support a joist placed thereon, said support means being arranged in stepped relation vertically and horizontally, the support means located adjacent said one end being of highest elevation; retainer means at the sides of the frame overlying each of said support means and defining, with said support means, transversely-spaced, horizontally extending slots for laterally receiving longitudinal edges of the joists when the frame is in its horizontal loading position and operative to prevent lateral displacement of the joists when the frame is in its vertical lifting position; and an extension integral with the frame and providing a lifting means at the opposite end of the frame by which the carrier can be tilted upwardly and lifted bodily by a crane to a position between said parallel roof elements, said carrier being movable successively downwardly and laterally by the crane so as to deposit the joists carried thereby singly and successively along and between the roof elements, said downward movement of the carrier releasing the joists from said slots.

5. A liftable carrier for use in placing joists to extend between parallel roof elements, comprising: a relatively wide rectangular frame tiltable on one end from a horizontal loading position to a vertical lifting position; caster wheels at the corners of said frame by which the carrier may be moved along a floor; a plurality of lon-

5

itudinally spaced uprights at the sides of said frame; horizontal bars connected between said uprights and providing horizontal supports upon which joists may be placed with a longitudinal edge of each joist disposed against a said upright; horizontal retainer fingers on said uprights each overlying a said horizontal bar, said fingers defining with said bars and said uprights horizontal recesses having their open ends disposed toward the opposite end of said frame to receive said longitudinal edges of the joists, said longitudinal edges being restable upon said uprights within said recesses when the carrier is tilted upwardly on said one end; and a rigid, integral lifting means at the said opposite end of the frame by which the carrier can be tilted upwardly and lifted bodily by a crane to a position between said parallel roof elements, said carrier being movable successively downwardly and laterally by the crane so as to deposit the joists carried thereby singly and successively along and between the roof elements, said downward movement of the carrier releasing the joists from said recesses.

6. A carrier as defined in claim 5 in which said frame, said uprights, said horizontal bars and said lifting means are structural shapes and provide a rigid, unitary structure, said carrier also including tie-rods extending between the sides of the carrier.

7. A carrier as defined in claim 5 including brake block means carried by said frame at its said opposite end and providing a fulcrum by which the carrier can be tilted on the floor.

8. A carrier as defined in claim 5, including block means carried by said frame at its said opposite end and providing a fulcrum by which the carrier can be tilted on the floor, and a pair of steering ropes detachably connected to the carrier at said opposite end thereof.
